DISPENSING DEVICE

Gerson Kaufman, Flushing, and Benjamin Linder, Larchmont, N. Y., assignors to Gynex Corporation, New York, N. Y., a corporation of New York

Application September 27, 1932, Serial No. 635,844

5 Claims. (Cl. 128—260)

This invention relates to dispensing devices, and more particularly to that type of dispensing devices wherein the material to be dispensed is extruded as required from the container.

5 The objects of the invention are to obtain an improved dispensing device of the character indicated in which the material may be extruded without shortening or squeezing the container; to provide such a device capable of being inserted 10 into a cavity of the human body and the material extruded at the inner end of the container; to enable the device to be promptly used without difficulty of preparation; to avoid the necessity of removing a cork or stopper; to provide a complete device capable of reuse with new containers; to secure simplicity of construction and operation; and to obtain other advantages and results as may be brought out in the following description.

20 Referring to the accompanying drawing, in which like numerals of reference indicate similar parts throughout the several views;

Figure 1 is a side elevation of a dispensing device in accordance with our invention, showing 25 the same ready to operate to extrude the material;

Figure 2 is a plan or end view of the device;

Figure 3 is a longitudinal sectional view, as upon line 3—3 of Fig. 1, but with the material 30 partly extruded;

Figure 4 is a similar longitudinal sectional view of the container alone before the material is extruded;

Figure 5 is an elevation of a modified construction, and

Figure 6 is a longitudinal sectional view thereof on line 6—6.

In the specific embodiment of the invention illustrated in said drawing, the reference numeral 40 10 indicates the container for material 11. The container is preferably of an elongated tubular construction with one end closed until used and the other end open except for an applied closure such as the cork 12 shown in Figures 1 to 4 or 45 the plunger head shown in Figures 5 and 6. In the construction of Figures 1 to 4, this open end of the container is shown as screw threaded, the screw-threads 13 being shown as pressed or moulded as part of the container. The cork 12 is applied to the container so as to be positioned substantially below the screw threads so as to leave a neck portion of the container which is not filled or otherwise obstructed.

As a feature of the present invention, we pro- 55 vide a container which, while initially closed at

one end as received by the consumer, yet it may be punctured or otherwise opened thereat. In the drawing, is illustrated a hole 14 at the tip end of the container, which hole, in Figures 1 and 4 is closed by an applied closure 15 such as paraffin. 5 However, it is to be understood that by use of puncturable material, such as a thin cellulose material, a preformed hole is not required, but may be formed by puncturing when the device is to be used.

In order to extrude the material within the container through the hole or puncture, we preferably provide means for forcing cork 12 longitudinally of the container. Carrying out this feature, we have illustrated a cap 16 hollowed out and threaded to be applied upon the threaded end of the container. Through this cap is slidably carried a plunger stem 17 having a plunger-head at its inner end adapted to retract into the hollowed-out part of the cap. The cap may accordingly be applied without disturbing the cork, and then by pushing inwardly upon the stem the cork will be slid, without any tilting, as far as desired. Preferably the container is of the right size so that its contents will comprise a single dose or application, and therefore the cork will be pressed to the punctured end of the container to extrude all of the material at one time under these circumstances.

The outer end of the stem 17 may conveniently be provided with an enlargement forming a finger piece or button 18. By shaping the exterior of the cap circumferentially concave, the same may be held between two fingers of one hand and the plunger pressed in with the thumb 30 of the same hand. After the material has been extruded, the instrument, including the container, is withdrawn from the body, the container removed and thrown away, and the cap, with its plunger, applied to a new container ready for use 35 again.

In order to make it convenient to puncture the hole 14, we have shown the outer face of the button 16 recessed, as at 19, with a size and shape of recess to nicely fit the end of the container when inserted therein. The container will accordingly be centered in the recess, and in the bottom of the recess is a point 20 which will consequently be guided to the center of the tip and puncture the tip thereat. Of course this 45 puncturing by point 20 has to be effected before the container is mounted upon the cap. The invention, however, is not restricted to use of this point nor of any point, as the closure for hole 14 may be of such nature so as to be forced out by 50 55

internal pressure created when pushing the plunger against the material.

In the construction of Figures 5 and 6, a unitary device including the plunger is shown, it being anticipated that the whole device will be discarded after use. The body portion of the device preferably provides an elongated container 21 the outer end of which provides a reduced neck 22 which expands thereabove into a cap portion 23, shown as hollow and large enough to receive the user's finger. A plunger 24 is provided with a plunger-head 25 within the container, initially near the neck thereof, and with a stem 26 extending through said neck into the expanded portion 27 of the device. A finger-piece or button 28 is provided on the outer end of the stem enabling the plunger to be conveniently pushed inwardly. The end of the expanded portion containing the plunger is preferably diagonally open so as to more readily accommodate the user's finger when pressing the plunger its full length.

The end of the container opposite from the neck is puncturable to permit extrusion of the material 11 within the container. Preferably the body portion is of inexpensive sheet material such as paper or cellulose material, in which event it is convenient to draw the end of the container together after the material has been introduced, and sealing by twisting the material 30 thereat, by paraffining the same if desired, and by divers other means.

Obviously other detail changes and modifications may be made in the construction and use of our improved dispensing device without departing from the spirit or scope of the present invention, and we do not wish to be understood as limiting ourselves to the precise details shown or described except as set forth in the following claims when construed in the light of the prior art.

Having thus described the invention, we claim:—

1. A dispensing device comprising an elongated container having one end thereof open and the other end closed, said closed end being constructed so as to rupture for discharging the contents, said open end having a cork within the same spaced inwardly from the open end for preventing withdrawal of the cork and discharge of the contents from the open end, and said container providing means between the cork and open end for retaining the cork spaced inwardly within the container.

2. A dispensing device comprising an elongated container having one end thereof open and the other end closed, said closed end being constructed so as to rupture for discharging the contents, said open end having a cork within the

same spaced inwardly from the open end for preventing withdrawal of the cork and discharge of the contents from the open end, said container having its wall next the open end spirally impressed with a screw thread thereby providing means between the cork and open end for retaining the cork spaced inwardly within the container.

3. A dispensing device comprising an elongated container having one end thereof open and the other end closed, said closed end being constructed so as to rupture for discharging the contents, said open end having a cork within the same spaced inwardly from the open end for preventing withdrawal of the cork and discharge of the contents from the open end, said container having its wall next the open end spirally impressed with a screw thread thereby providing means between the cork and open end for retaining the cork spaced inwardly within the container, and means for pushing the cork longitudinally inward of the container, said means comprising a cap threaded on to the exterior of said spirally threaded portion of the container and a plunger slidable in said cap and having a plunger head of less diameter than the cork and insertable through the impressed screw threads of the container.

4. A dispensing device comprising in combination with a container having one end screw-threaded and receiving a cork inset from said end, the opposite end of the container adapted to be opened in use, a cap adapted to be applied to said screw-threads, and a plunger passing through said cap and having an inner end adapted to engage and push the cork toward the opened end of the container.

5. In combination, an elongated capsule-like container for substantially complete and unprotected insertion in a body orifice, one end of said container being closed and the other end open, said closed end being constructed so as to rupture for discharging the contents in said body orifice, said open end having a cork for retaining the contents and also having means for mounting the container by its said open end for maintaining the container unenclosed for substantially its entire length when mounted, and means applicable to the said mounting means for supporting the said container in use, this last said supporting means providing operative mechanism for impelling the cork and contents longitudinally of the container toward the closed end for impelling the contents through the rupture thereof.
